RELEASABLY CLOSED OPENING FOR CONTAINERS

Filed May 10, 1929

Inventor
John Edward Thebaud

UNITED STATES PATENT OFFICE

JOHN EDWARD THEBAUD, OF NORTH MERCHANTVILLE, NEW JERSEY

RELEASEABLY CLOSED OPENING FOR CONTAINERS

Application filed May 10, 1929. Serial No. 362,010.

Like figures of reference refer to like parts.

This invention relates to releasably closed openings for containers, more particularly for milk bottles.

5 Milk bottles are commonly formed with a narrow annular ledge inside the mouth of the bottle and below the top, providing a seat for the flat, paraffined, cardboard cap, the edge of which fits tightly, all around, into the 10 bottle mouth forming a continuous and complete seal for closing the bottle. These caps, with the formation of the bottle, as now used, are very difficult to remove, unless a sharp instrument is forced into the cap over the unsupported area within the seat. If the bottle happens to be full, any sudden pressure upon this unsupported area of this cap will cause splashing.

It is therefore one of the objects of my invention to so form the bottle or container, inside the mouth thereof, that one will be able to get hold of the cap to remove it, by the use of an ordinary fork prong or similar instrument forced under the cap edge, rather 25 than within the central unsupported area of the cap.

In order to penetrate below the cap at its edge, to pry it up, there must, in any event, be an unsupported area and this I provide 30 outside the cap seat itself, by surrounding the seat with an annular groove, or depression, next to and inside thereof the inner wall of the bottle mouth, so that the cap edge, at any point, where it is normally in frictional, 35 sealing contact, can be penetrated or gotten under with a pointed instrument to pry the cap off.

Another object is to provide a firmer seating for the cardboard cap.

40 Various forms of my invention adapted to other forms of containers, as well as to milk bottles, are illustrated in the drawings, are hereinafter described, the use is explained and what I claim is set forth.

In the drawings,

Figure 1 is a plan of a top of a milk bottle and cap embodying my invention.

45 Figure 2 is a section taken on the line 2-2 of Figure 1.

55 Figure 3 is a perspective view of an ordinary flat cardboard milk bottle cap.

Figure 4 is an enlarged section of one side of bottle top, showing the groove, cap and seat more plainly.

Figure 5 is a sectional view of one side of a container top, of sheet material.

Figure 6 is a modification, in section, showing my invention embodied, as a seating, in the mouth of a sheet metal rimmed fibre, or 60 paper container.

Figure 7 is a section of a fragment of another form embodying my invention.

In the figures, referring particularly to Figures 1, 2 and 3, tightly fitting within 65 the wall 10, of the mouth 11, of the upper fragment of milk bottle 12, is the usual form of flat paraffined cardboard cap or disc 13, resting in contact with the narrow annular seat 14, which is spaced from the wall 10, 70 and is surrounded by the annular groove 15. The edge of the cap 13 is thus left unsupported, except for its forced, peripheral frictional contact with the wall 10.

75 In order to drain the groove 15, I provide vertical channels 16, on the inner wall of the bottle, reaching from the bottom of the groove 15, down toward the inside of the neck of the bottle.

80 In Figure 4, the groove 15 is shown to be conically inclined at 17, at a less angle to the plane of the cap, where it meets the seat 14, than is shown in Figure 2. 13^a is the bent-down, broken line position of the edge of the cap 13, into the groove 15.

85 In Figure 5 we have a sectional view of a fragment of a sheet metal container mouth 18, having a rolled edge 19. In frictional contact with the inner wall 20, is the cap 13, and below the edge 21, of which, in this figure, is the groove 22. 23 is the body of the container. 21^a is the bent-down, broken line position of the cap edge 21, into the groove 22.

90 In Figure 6 I show a fragment of a fibre or paper container 24, terminating in a top edge 25. Fixed to the body of the container 24, is the ring 26, of sheet material, having a skirt 27, fixed on the wall of the container 24, and positioned a little below the edge 25. The ledge 28, in conjunction with the wall 29, 95 100

forms with the upper part of the container, an annular groove 30, below and outside of the edge 25. The top edge 25 forms a seat for the cardboard cap 31, which is in frictional contact with the wall 29, of the ring 26.

5 In Figure 7 is shown an extra circumferential ledge 32, forming an auxiliary seat, surrounding the groove 15, on a level with the seat 14.

10 The construction above described in connection with the figures, provides means enabling one to force the point of an instrument 33, such as the prong of a fork, below the edge of the cap 13 at its peripheral, frictional and 15 continuous contact with the wall 10, down into the groove 15, to pry off the cap 13.

I have found it easy to lift the cap 13 with the prong of a fork, by moving the prong forward around the cap edge breaking its 20 peripheral, frictional contact with the wall, after forcing the point of the prong beneath the edge of the cap into the groove. The cap edge, in this case, easily slides between the thumb and the fork prong during the circumferential movement and is readily lifted off.

25 In case milk enters the groove 15, it can find its way back into the bottle, down by way of the vertical channels.

30 In connection with the cap 13, it will be observed that if the present diameter of cap is retained, then the opening in the top of the bottle, at the cap seat, will be a little smaller, so as to allow space, within the wall 10 for the groove 15 below the cap edge. This reduction in the diameter of the cap seat somewhat reduces the unsupported central area of the cap, and coupled with the fact that the seat is radially spaced from the frictional contact of the cap edge with the inside 40 wall of the bottle mouth, there is a stiffening effect given to the cap when in place, affording a stronger seating to the cap in the bottle.

45 This invention is applicable to other forms of containers than milk bottles as above pointed out. Paper cups for ice cream and other food stuffs wherein a cardboard cap is used, can have their tops formed embodying my invention for easy opening.

50 Inasmuch as other modifications of my invention, other than those herein illustrated and described, can be made without departing from the spirit and scope of my invention, I desire to include all forms which come within the purview of the following claims.

I claim,

1. A releasably closed opening for a container comprising in combination, a mouth wall to said opening, a seat spaced from said wall, a groove next to said wall, surrounding said seat and below the same and a flat cap resting upon said seat, having its edge in contact with said wall and having a portion of said cap between its edge and said seat un-

supported and spaced from the bottom of said groove.

2. A milk bottle top and releasably-closed opening comprising a thickened mouth, having a continuous and unbroken internal upright wall, a cap seat having the plane thereof passing thru the lower part of said wall, said seat being spaced within said wall, an annular grooved portion to said opening between said seat and said wall, positioned below the plane of said seat and a flat cardboard cap, tightly fitting within the lower part of said wall in continuous peripheral contact with said wall, and in contact with said seat, and extending over said grooved portion in spaced relation with the bottom of said groove, whereby a pointed instrument can be forced beneath the edge of said cap, into said groove to pry said cap off said top.

3. A releasably closed opening for a container, comprising in combination, a mouth wall to said opening, an annular ledge within said wall, forming a cap seat, a second cap seat in the plane of said first mentioned cap seat, smaller than the same and in spaced relation with the same, an annular groove between said seats, below the plane of said seats, and a flat cap in contact with said seats, in spaced relation with the bottom of said groove.

4. A releasably closed opening for containers, comprising a container mouth wall, a cap seat spaced within said wall, a groove surrounding said seat next to said wall, and positioned below the plane of said seat, draining channels leading from said groove into the cavity of said container, and a cap positioned on said seat in spaced relation with the bottom of said groove, the edge of said cap being in continuous peripheral contact with said wall.

5. In a container having a mouth wall, a cap seat and a cap, a releasably closed opening affording means permitting the use of a pointed lifting instrument thrust below the edge of the said cap while in place on said seat, comprising an inner mouth wall, a cap seat spaced horizontally within said wall and in the plane of the lower portion of said wall, a cap resting on said seat and in frictional peripheral contact, continuously, with the said lower portion of said wall, and a grooved portion to said opening, positioned to be wholly within the said lower portion of said wall and surrounding said seat, and below the plane of said seat, affording a space below the edge of said cap on said seat, into which to enter a pointed instrument, at and below the said cap edge, whereby said cap can be readily raised off said seat by lifting from below, with the point of said instrument.

6. A releasably closed opening for a container, having a body wall, said opening com-

prising, a ring integral with the said body wall, said ring being of sheet material, and formed having a seat portion, a grooved portion below the plane of said seat, a wall portion to said ring, having its inner surface merging below into the converging surface of said grooved portion, and a cap disc in peripheral, frictional contact with the lower part of said wall portion, affording a construction, whereby a pointed instrument can be thrust below said edge into said groove to lift off said cap from said ring.

JOHN EDWARD THEBAUD.
